UNITED STATES PATENT OFFICE

JOSEPH RICHARDSON, OF SURREY HILLS, AND ALBERT LANCELOT HENDERSON, OF KENSINGTON, VICTORIA, AUSTRALIA.

HEATER FOR AUTOMOBILES.

Application filed February 26, 1924. Serial No. 695,177.

To all whom it may concern:

Be it known that we, JOSEPH RICHARDSON, a subject of the King of Great Britain and Ireland, residing at 13 Barton Street, Surrey Hills, in the State of Victoria, in Australia, and ALBERT LANCELOT HENDERSON, a subject of the King of Great Britain and Ireland, residing at 39 Ormond Street, Kensington, in the State of Victoria, in Australia, have invented certain new and useful Improvements in Heaters for Automobiles, of which the following is a specification.

This invention provides apparatus of that class whereby, by utilizing an engine exhaust, water will be heated, and circulated in a radiator in an automobile, (hereinafter called a car) or the like, there being means if desired to allow of drawing off water for use. Our apparatus may be wholly or partly detached from the car, but ordinarily will be kept installed ready for use, and the comfort of car occupants will be increased in cold weather when heat is thus provided.

In the drawings herewith—

Figure 1 shows in side sectional elevation our construction installed in a motor car; but that construction can be varied in minor details to suit the make of car or the like, while retaining matter hereinafter claimed.

Figures 2 to 4 are on an enlarged scale.

Figure 2 is a partly sectional view of our apparatus detached.

Figure 3 is a plan of a casing which contains exhaust passages, one of which contains a boiler.

Figure 4 is a sectional plan of the said casing.

In these drawings 23 is a main water tank, and 24^a, 24^b is a heat radiator shown located for use as a footwarmer, through which water from the tank will circulate, the radiator being of any suitable description, the footwarmer shown having, however, some advantages. This radiator comprises a superposed vessel 24^b connected with an undervessel 24^a by straps 24^c, and a tubular neck 29 which ensures water circulation, arrows in Figure 2 showing the direction of such circulation.

The tank 23 is shown, by way of example, attached to the motor car seat back 25, and, when desired, carries a water gauge, not shown. It has any suitable filling opening 23^b, and may have partitions 23^a to

guide water in circulation. This tank has an air vent pipe 27 the exit of which is above a receiver 28, so that if water splashes up through the vent 27 it will not do so objectionably.

The tank is best located above the car floor, and above the vessels 24^a, 24^b. These parts 23, 24^a, 24^b are connected by tubing to parts of our apparatus at a lower location, and shown below the car floor. The heat radiating vessels may, however, be located in various convenient positions; and the radiators have, in our preferred construction, supporting framing 31 which allows of adjusting the radiator to change its position. These radiators may be protected by wire screening 32 to prevent persons touching their hot surfaces.

For exhaust receiving purposes we provide an elongated casing 1 of suitable dimensions, containing longitudinal flues 2, 3, having at one end a common inlet 4, and at the other end, a common outlet 5. The flues are separated by a partition 15, which when desired is heat insulating, being shown containing asbestos or the like 16. The inlet 4 is connected to the engine exhaust pipe 6 (Figure 1) between the engine and the sound muffler 7.

At opposite ends of the partition are pivoted sections 8 and 9, having operating means so that they will be moved simultaneously, and will close either flue 2 or flue 3, directing the hot gases in exhaust pipe 6 through the unclosed flue.

The sections 8 and 9 are heat insulating, being shown containing asbestos or the like 8^a, 9^a.

The exhaust can be directed partly through each flue when a modification of heating effect is required, by adjusting sections 8 and 9 appropriately. Each flue is large and straight enough to prevent the occurrence of objectionable back pressure of the exhaust.

Flue 2 contains a water boiler which is an elongated boiler 17 capable of withstanding severe stresses. In this boiler the hottest water will be produced by directing the exhaust gases through flue 2, and even steam may be generated. At other times the exhaust gases are directed by the door 8 into flue 3 which offers negligible resistance to the exhaust. Flue 2 offers greater resistance, by reason of the presence of the

boiler, but even the latter resistance is relatively slight, the back pressure aforesaid being avoided. Each door 8 and 9 is relatively long, and extends at only a slight obliquity to the flow of exhaust, the oblique surfaces directing exhaust gases as aforesaid, shutting exhaust off from either flue as required. To allow of operating the doors they have pivotal projections 10 extending outside the flue casing, where each projection carries an arm 11, these arms being pivoted to a connecting link 12, and controlled by a rod 13, extending from an extension 14 of one arm 11, to means by which an attendant can set the doors from time to time in desired positions. These means are shown as a lever 13^a, the position of the same being, in practice, wherever convenience requires.

20 The boiler is secured in position by a strap 20, and has a drainage pipe 22 and cock 21. Our elongated boiler 17 is annular in cross section, and is set so that it leaves a space all round its exterior for passage of exhaust, 25 and a space along its interior for passage of exhaust at the same time, the exterior and interior surfaces being conical, the exterior enlarging and the interior contracting towards the rear to provide inner and outer 30 exhaust contact surfaces. These exterior and interior surfaces thus diverge from one another from the exhaust inlet towards its outlet. The front end of the boiler is circular as shown at 17^a, and the diverging and 35 converging exterior and interior walls produce a wedge shape, the boiler thus offering negligible resistance to exhaust gases; but owing to the conical surfaces aforesaid the boiler is relatively thick at its rear, and 40 has an end 17^b of substantial area, which is utilized for connection thereto of inlet and outlet water circulating pipes 18 and 19, which are spaced apart and extend to the relatively large heat radiator 24^a, 24^b. These 45 pipes are shown attached one above the other to the boiler end.

We provide one or more taps 33, for drawing off water when desired, and the radiator may be fitted with a thermometer.

50 The boiler is connected by pipe 19 to the top of the radiator, 24^b, which has a vent 26 (with a cock 26^b), and 26^a is a water overflow receiver. This vent is necessary to allow of air escape when the apparatus is being charged with water, and it will also allow surplus water to escape. But when the radiator is charged for use the cock 26^b is closed.

We provide cocks 34 on pipes 18 and 19 for regulation of the circulation of the water, and to stop the circulation if desired when the exhaust is not being utilized.

For safety purposes we find that an outlet is desirable from one of the pipes which communicate with the boiler, and this out-

let is shown as a pipe 30 extending from pipe 18 to a suitably high point, that is the top of tank 23. This pipe will not normally act as a circulation element, but it will, when the emergency occurs, provide a passage for boiler steam, or steam and water, especially when the cocks 34 are closed. Ordinarily, however, an occupant of the car would direct the exhaust through passage 3 before the water in the boiler became hot enough to generate steam freely; if steam were produced the first effect would be to increase the heat in the radiator, and then the heat in tank 23, as heated water would rise through pipe 18^a. The insulation between the flues 2 and 3 retards heating of flue 2 when the exhaust gases are passing through flue 3, and thus overheating of the boiler water is guarded against.

To prevent siphonage of water from tank 23 through pipe 27, or pipe 30, we provide air holes 27^a and 30^a in pipes 27 and 30.

The boiler, even if dry, will withstand the heat of the exhaust.

We claim:—

1. In an automobile heating apparatus including an exhaust pipe, a boiler element, and water circulation means, the combination of a casing adapted to allow the passage of exhaust gases therethrough and enclosing said boiler element, a partition in said casing, and means for adjusting said partition to allow desired quantities of exhaust gases to pass through and around said boiler element.

2. In an automobile heating apparatus including an exhaust pipe, a boiler element, and water circulation means, the combination of a casing adapted to allow the passage of exhaust gases therethrough and enclosing said boiler element, a partition in said casing comprising one fixed section and two swinging sections pivotally supported by opposite edges of said fixed section, and means for adjusting said swinging sections to allow desired quantities of exhaust gases to pass through and around said boiler element.

3. A water heater for use in conjunction with the exhaust gases from an engine, comprising an annular liquid-containing chamber which is triangular in longitudinal section with the apex of the triangle turned toward the oncoming gases, said chamber being adapted to allow the passage of separate streams of exhaust gases through and around the chamber, and inlet and outlet means for the liquid in said chamber, said means communicating with the wall forming the base of said triangle.

In witness whereof we have hereunto set our hands.

JOSEPH RICHARDSON.
